Primary Examiner — Shawn T Gingrich*(74) Attorney, Agent, or Firm* — Asgaard Patent Services, LLC; F. Wayne Thompson, Jr.**(57) CLAIM**

The ornamental design for an angled pressure switch, as shown and described.

DESCRIPTION

FIG. 1 is a top, front, right side isometric view of an angled pressure switch;

FIG. 2 is a bottom, back, left side isometric view of the angled pressure switch shown in FIG. 1;

FIG. 3 is a front view of the angled pressure switch shown in FIG. 1;

FIG. 4 is a right side view of the angled pressure switch shown in FIG. 1;

FIG. 5 is a back view of the angled pressure switch shown in FIG. 1;

FIG. 6 is a left side view of the angled pressure switch shown in FIG. 1;

FIG. 7 is a top view of the angled pressure switch shown in FIG. 1; and,

FIG. 8 is a bottom view of the angled pressure switch shown in FIG. 1.

The broken lines shown in the drawings represent portions of the angled pressure switch that form no part of the claimed design.
